UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

GAS RETORT.

Application filed August 31, 1921, Serial No. 497,363, and in Germany March 6, 1918.

(GRANTED UNDER THE PROVISIONS OF THE ACT OF MARCH 3, 1921, 41 STAT. L. 1313.)

This invention relates to gas retorts, and the improvements of the invention are especially applicable to retort ovens constituted of several retorts assembled by a joint 5 enveloping structure.

The heating of the retort ovens for manufacture of illuminating gas is usually carried out in such manner that the fuel gases are fed hot to the oven, i. e. with their 10 sensible heat, directly from the built-in or adjoining gas generators; the air to support combustion is, on the other hand, suitably preheated with the aid of the waste heat in two-chamber heaters. The feeding of the 15 hot gases in this connection has the drawback that the dust content of the gases is taken along into the oven, whereby strong scorifications are caused which result in the oven being destroyed in a comparatively 20 short time. The heat recovery by means of two-chamber heaters has a very poor degree of efficiency, inasmuch as it operates only for the air, and only a very imperfect utilization 25 of the surplus heat available is effected thereby.

These disadvantages were quite generally removed in connection with gas fired plants according to the Patent 219,733 by operating such oven plants with heat recovery both 30 of the air and of the gas, i. e., in single-chamber heaters or so-called regenerators or heat storers, whereby the facility is afforded of cooling and thus practically ridging from dust the gases coming from the 35 gas generators, while the excellent efficiency of this heat recovery permits of a practically perfect utilization of the surplus of the waste heat. By means of the present invention, the advantages of this heating 40 method are to be rendered utilizable for retort ovens of the customary construction, i. e., for such ovens in which a large number of retorts, usually nine in number, are assembled in each case within a shell or envelope 45 so as to form a structural and operating unit. This oven construction has given good results and can also be easily adapted to the existing plants, and also affords the possibility of effecting a simple reconstruction 50 of old plants.

According to the invention, the retort group disposed in an envelope is so con-

nected in each case with two pairs of regenerators operated in the well known manner on the alternating draft principle that 55 the retorts are always surrounded and swept by ascending gases on one side and on the other side by the descending gases and vice versa. In this manner, such a retort group 60 together with the heat storers forms a unit 65 which can be operated, regulated and, if necessary, disconnected by itself. The structural means for carrying out the heating for such a retort group by means of two pairs of heat storers consists in providing under 70 each half of the retort group a plurality of, in the present instance three, distributing chambers for the fuel, two of which are interconnected and also connected with one of the pairs of heat storers, while the central distributing chamber is connected to the second heat storer. While in this connection from the two first mentioned distributing chambers the gaseous medium, for instance the fuel gas, is conducted into the 75 heating flues through simple ducts, two ducts each emanate from the central distributing chamber towards the right and the left in order to introduce the second gaseous medium, for instance the air, into the heating 80 flues at points in proximity with the gas inlets.

In addition to the general objects recited above, the invention has for further objects such other improvements and advantages in 85 construction and operation as are found to obtain in the structures and devices herein-after described or claimed.

In the accompanying drawings, forming a part of this specification and showing, for 90 purposes of exemplification a preferred form and manner in which the invention may be embodied and practised, but without limiting the claimed invention specifically to such 95 illustrative instance or instances:

Figure 1 illustrates a vertical section through retorts and gas regenerators of a specific application of the invention in a retort oven consisting of nine retorts;

Fig. 2 is another vertical cross section of 100 the same, and

Fig. 3 is a vertical section on the axis of the air regenerator.

In the shell or envelope 10 the retorts 11,

in the present instance nine in number, are arranged; the retorts may be made up, as shown, of individual molded pieces and placed in the inclined position shown. The 5 retorts are supported by the cross walls 12 and the inclined walls 12', the construction providing series of heating flues which surround the retorts. Below the envelope 10 the regenerators 13 for air and 14 for fuel 10 gas are arranged. On one side, these regenerators are connected with the waste heat channel 16 by channels 17 and connecting pipes 18. The gas is introduced into the 15 gas regenerators 14 through the port 19 of the sole channels and the air into the air regenerators 13 through the ports 20, of the sole channels. These connections are arranged in the well known manner in order to make it possible to operate the heat storers 20 alternately as gas and air heaters and as waste heat storers, by effecting the usual reversal operation, at the end of each reversal period, usually about a half-hour.

The regenerators 14 communicate with 25 the distributing chambers 21' through shafts 21, in which connection it is possible, by slides 22, to effect a throttling of these shafts for the purpose of regulating the gas flow. From the distributing chambers 21' the gases 30 go directly into the combustion chamber through nozzle-like ducts 23 and 23'.

The air regenerator communicates with the distributing chambers 25' through shafts 25 which can be regulated by slides 26, the 35 distributing chambers 25' being placed between the chambers 21, 21'. From the chambers 25' emanate nozzle-like ducts 27 and 27' towards the right and the left in order to terminate near the gas nozzles 23 and 40 23'. In this manner a uniform distribution of gas and air to each burner place is possible, when such regenerators are operating for inflow, while on the waste heat side of the retort group these perforations all serve 45 for drawing off the waste heat into the two regenerators of the opposite side. In this manner it is possible to heat such a retort group in a wholly uniform manner, like a nine-retort oven, and to get along in this 50 connection for each oven unit with the minimum number of regenerators for a heat recovery with single chamber heaters, i. e., two pairs of such. The division of the chambers 21' or 25' into two compartments which 55 can be regulated by slides 22 or 26 has for its object to compensate possible irregularities in the basic distribution of the fuel, such as might for instance be caused by the slanting or inclined position of the retorts.

60 The invention, as hereinabove set forth, is embodied in a particular form of construction, but may be variously embodied within the scope of the claims hereinafter made.

I claim:

65 1. In a gas retort construction, in combi-

nation: a plurality of retort chambers assembled in a joint envelope; heating flues surrounding said retort chambers, said flues being operatively disposed into reversibly-operable inflow and outflow groups; reversibly-operable regenerators operatively disposed into interchangeable outflow and inflow groups the reversal being laterally to said retort, the inflow-operating group embodying gas and air regenerators; a front 75 and a back pair of distributing chambers communicably connected with said gas regenerator and each one of said pair with one of two series of inflow-operating flues; and a front and a back single distributing 80 chamber interposed between the two aforesaid distributing chambers and communicably connected with both the air regenerator and with the two series of inflow-operating flues; substantially as specified. 85

2. In a gas retort construction, in combination: a plurality of retort chambers assembled in a joint envelope; heating flues surrounding said retort chambers, said flues being operatively disposed into reversibly-operable inflow and outflow groups; reversibly-operable regenerators operatively disposed into interchangeable outflow and inflow groups, the reversal being laterally to said retorts, the inflow-operating groups embodying gas and air regenerators; a pair of distributing chambers communicably connected with said gas regenerator and each one of said pair with one of two series of inflow-operating flues; and a single distributing 95 chamber communicably connected with both the air regenerator and with the two series of inflow-operating flues; substantially as specified. 100

3. In a gas retort construction, in combination: a plurality of retort chambers assembled in a joint envelope; heating flues surrounding said retort chambers and operatively disposed into two groups; regenerators operatively disposed into two groups; 105 two pairs of distributing chambers paralleling said retorts respectively communicably connecting one of the regenerators of different groups with said groups of heating flues; and two single distributing chambers paralleling said retorts respectively communicably connecting the other regenerators of said groups with the groups of heating flues; substantially as specified. 115

4. A gas retort construction, in combination: a plurality of retorts assembled in a joint envelope; two air regenerators; two gas regenerators; said regenerators being divided into groups, one for inflow and one for outflow, the flow in said groups being reversible laterally of said retorts; each group consisting of an air regenerator and a gas regenerator; each group having three distributing chambers paralleling the retorts, one of said chambers communicably 120

connecting one of said regenerators with a plurality of flues of two series of flues, one at each side of a row of retorts in said group, the other two chambers communicably connecting the other regenerator with the same said flues.

5. A gas retort construction, in combination: a plurality of retorts assembled in a joint envelope; two air regenerators; two 10 gas regenerators; said regenerators being divided into groups for inflow and outflow laterally of the retorts, each group consisting of an air regenerator and a gas regenerator; each group having three distributing 15 chambers paralleling the retorts, one of said chambers communicably connecting one of said regenerators with a plurality of flues

of two series of flues, one at each side of the retorts in said group, the other two chambers communicably connecting the other regenerator with the same said flues; said single distributing chamber being located in the middle of said two distribution chambers.

20 6. A gas retort construction according to claim 4 characterized by there being a plurality of said distributing chambers arranged longitudinally of said retorts.

7. A gas retort construction according to claim 5 characterized by there being a plurality of said distributing chambers arranged longitudinally of said retorts.

30 HEINRICH KOPPERS.
